UNITED STATES PATENT OFFICE.

WHITNEY M. FRYE, OF WILTON, NEW HAMPSHIRE.

CARD.

Application filed November 16, 1923. Serial No. 675,223.

To all whom it may concern:

Be it known that I, WHITNEY M. FRYE, a citizen of the United States, residing at Wilton, county of Hillsborough, State of

5 New Hampshire, have invented a certain new and useful Improvement in Cards, of which the following is a specification, reference being had therein to the accompanying drawings.

10 My invention relates to cards, and especially, although not exclusively, to hand cards for use in carding animals, and has for one of its objects the provision of a hand card which has exceptional strength, and one in 15 which the handle and back will consequently not be readily broken when subjected to rough usage. My hand card is also adaptable for use in hand stripping cards for textile mills.

20 In the past, great difficulty has been encountered in the use of hard cards due to the fact that the handles which are attached to the back of the cards frequently split or cause the back of the card to split. This

25 difficulty has been largely due to the manner of attaching the handle to the back and other weaknesses in the construction of the cards. In the construction of my hand card, the end of the handle, which is attached to

30 the back of the card, is sawed so as to provide an inclined surface which extends nearly across the back of the card. I provide a tongue on the handle which is adapted to enter a curved slot in the back of the card.

35 The tongue, due to its engagement in the slot, firmly supports the handle and, together with the screws or nails, which secure the inclined surface of the handle to the back, provides a construction which will 40 not break and which will outlast any of the similar articles previously made.

Another advantage of my construction of the back and handle is that both of these parts can be made very cheaply, requiring a 45 minimum of labor. The inclined surface which is secured to the back of the card, and the tongue, can be made in one operation by means of three concentric circular saws one of which cuts the inclined surface of the 50 handle and the upper surface of the tongue which is parallel thereto; another cuts away the wood the proper amount so as to leave the tongue, and the third cuts the lower surface of the tongue making it also parallel to 55 the inclined surface of the handle.

Apart from the improved construction of

the handle and back, I also provide improved card clothing which is attached to the back of the card and carries the teeth. The card clothing which constitutes a part 60 of my invention may be made in sheets of any size and used as the carding elements in carding machines, such as those used in making textile products. Heretofore it has frequently been necessary to discontinue using 65 a hand card due to the fact that the teeth would become bent so that they would no longer effectively do the work. In order to support the teeth against bending, I punch the clothing so as to provide burrs on one 70 side. These burrs project from the surface of the clothing and brace the teeth against movement in the opposite direction from which the card is drawn in use.

75 My invention will be fully understood from the following description when taken in connection with the accompanying drawings and the novel features thereof will be pointed out and clearly defined in the claims at the close of this specification. 80

In said drawings:

Fig. 1 is a side elevation, partly in section, taken in the plane indicated by the line 1—1, Fig. 2, showing the manner of attaching the handle to the back of the card. 85

Fig. 2 is a fragmentary plan view of the card.

Fig. 3 is a longitudinal section of the handle, part of which is broken away.

Fig. 4 is an enlarged fragmentary section taken on the line 4—4, Fig. 5.

Fig. 5 is a fragmentary plan view of a portion of the card clothing.

Fig. 6 is a fragmentary section of the card taken on the line 6—6, Fig. 1. 95

Referring now to Fig. 1, at 11 is shown my improved handle attached to the back 12 of the card. Card clothing 13 is secured, as by tacks 14, to the lower face of the back and is provided with teeth 15 projecting 100 downwardly therefrom. The handle 11 is sawed in the manner described above so as to provide the inclined surface 16 which is secured to the back 12 by nails or screws 17. The handle 11 is positioned midway of the back 12 and is also provided with a tongue portion 18. The tongue portion 18 is cut so as to have upper and lower surfaces 19 and 20 which are parallel to the inclined surface 16. In the sawing operation, due to 110 the fact that circular saws are used, the end 21 of the tongue portion 18 is left in the

form of a curve. The back 12 is provided with a curved slot 22 in one side which is adapted to receive the tongue portion 18 of the handle 11. When the handle 11 is assembled with the back 12, the tongue portion 18 enters the slot 22 until its ends 23 are in engagement with the rear wall of the slot. The nails 17 are then driven through the handle 11 and back 12.

10 The carding material 13, which supports the teeth 15, may be of leather, fibre, or any laminated material which will permit the burrs 24 to be punched up therefrom. In the construction of the carding material, I punch rows of staggered holes through the material by means which punch a portion of the material up from the surface so as to form the burrs 24. The burrs 24 are semi-circular and project from one surface 20 of the carding material. The teeth 15 are made in pairs and are bent adjacent their ends in the direction in which the hand card is to be moved in use. The burrs 24 extend up the back of the teeth 15 and prevent the teeth from bending back into a position in which they would no longer be effective.

25 Having thus described my invention, what I claim is:

30 1. In a hand card, the combination with a

back having card clothing on one face and provided with a closed slot in one edge thereof, of a handle secured to said back and extending substantially the whole distance across the same, said handle having a tongue portion for reception in said closed slot.

2. In a hand card, the combination with a back having card clothing on one face and provided with an arcuate closed slot in one edge thereof, of a handle secured to said back and extending substantially the whole distance across the same, said handle having a tongue portion projecting into said slot, the end of said tongue portion being oppositely curved from said slot.

3. In a hand card, the combination with a back having an arcuate closed slot in one edge thereof, of a handle secured thereto extending substantially the whole distance thereacross, one end of said handle being sawed to provide an inclined surface for attachment to the back, and a tongue portion projecting in the direction of said inclined surface and extending into said slot, the sides of said tongue portion being parallel to said inclined surface.

45 In testimony whereof I affix my signature.

50 WHITNEY M. FRYE.
